UNITED STATES PATENT OFFICE.

WILLIAM MURRAY MORTON, OF DARVEL, SCOTLAND.

DESIGN FOR CARPET.

40,446.

Specification for Design.

Patented Jan. 11, 1910.

Application filed November 9, 1909. Serial No. 527,113. Term of patent 3½ years.

To all whom it may concern:

Be it known that I, WILLIAM MURRAY MORTON, a subject of the King of Great Britain, and resident of Hastings Square, Darvel, Ayrshire, Scotland, have invented a new, original, and ornamental Design for Carpets, of which the following is a specification, reference being had to the accompanying drawing, forming a part thereof.

The figure is a plan view of a portion of a carpet embodying my new design.

The design comprises a plain center and a contrasting border formed of large rose clumps.

I claim—

The ornamental design for a carpet, as shown, and described.

WILLIAM MURRAY MORTON.
